ABSTRACT OF THE DISCLOSURE

Apparatus for batting practice including a framework comprising a first upright having a pair of vertically spaced, laterally extending arms mounted thereon for vertical shifting movement therealong. A plurality of laterally spaced fingers, of graduated lengths, are swingably mounted on each of the arms and extend toward corresponding fingers on the opposite arm to define a gap between the outermost ends of the fingers, through which gap a bat may be swung. A ball is tethered in horizontally spaced relationship from the gap to provide a target for the batter. The ball is mounted so that vertical movement of the finger-supporting arms causes corresponding vertical movement of the target ball.

This invention relates to athletic equipment and, more particularly, to apparatus for giving a baseball or softball batter practice in carrying out the swing of his bat toward a ball. The time interval involved in carrying out a swing at the ball in games of this type is of extremely short duration so that the batter must rely upon a "feel" for controlling the direction of his swing. The "feel" is not entirely a natural response and must be learned and practiced if the batter is to be able to control the swing of the bat within the interval involved in a manner for making proper contact with the ball. The problem is especially acute if the ball is following a changing trajectory as it travels past the batter.

It is theorized that one of the chief reasons for batters either missing a pitched ball entirely or failing to make solid contact with the ball is the inability to swing the bat through the path of travel which is desired by the batter as he watches the ball move along its trajectory.

Accordingly, it is an important object of this invention to provide apparatus which will sense and reveal to a batter the path of swing of his bat through a defined area, thereby permitting him to correct his swing until he can almost instinctively swing the bat where he desires.

It is another object of this invention to provide batting practice apparatus which provides a visual target in a location approximating the location of a ball when the batter should commence his swing.

Still a further object of the instant invention is to provide such apparatus wherein the target ball and swing-sensing assembly are simultaneously adjustable and are automatically correlated to permit practice of the swing through a variety of planes.

Yet another object of this invention is to provide apparatus which may be quickly and easily fabricated from relatively inexpensive and readily available materials, yet which is capable of providing a batter with a sensing device to accurately indicate any deviation from the desired path of swing of the bat, and to inform the batter of the direction and amount of such deviation.

These and other objects of this invention will be further explained or will become apparent from the following description, claims and drawing.

In the drawing:

FIGURE 1 is a perspective view on a reduced scale of apparatus embodying the principles of this invention;

FIG. 2 is a fragmentary, end elevational view of the swing-sensing assembly;

2

FIG. 3 is a schematic diagram of the cable and pulley system on the scale of FIG. 1 illustrating the interconnection of the ball with the swing-sensing assembly;

FIG. 4 is an enlarged, fragmentary, vertical, cross-sectional view through a junction of the horizontal connecting member and one of the uprights illustrating one of the pulleys and a portion of the connecting element;

FIG. 5 is a fragmentary, horizontal, cross-sectional view through the horizontal connecting member illustrating the leveling device in elevation, one of the legs appearing fragmentarily in its folded position; and

FIG. 6 is a fragmentary, side elevational view of the counterweight assembly, parts being broken away to reveal details of construction.

Apparatus embodying the principles of this invention includes a frame broadly designated by the numeral 10 comprised of a pair of horizontally spaced uprights 12 and 14 interconnected by a connecting member 16 and supported by leg assemblies 18 and 20 respectively. Upright 15 may comprise an elongated, tubular member such as a pipe 22 or the like which is interconnected at its lowermost end by releasable means 24 to a tubular, vertically extending section 26 communicating with member 16 through an elbow 28. Member 16 is, in turn, hollow and communicates through an elbow 30 with a vertically extending, tubular member 32. A pipe 34 of greater diameter than member 32 is telescoped over the latter and carries, at its uppermost end, a short pipe section 36 which communicates with a laterally extending boom 38 through an elbow 40.

Upright 14 includes an elongated sleeve 42 telescoped over pipe 22 and is provided with a thumbscrew 44 or the like for releasably securing sleeve 42 at any predetermined position along the pipe 22. Sleeve 42 comprises a part of a sensing assembly 46 which includes a pair of vertically spaced, laterally extending arms 48 and 50 respectively. The uppermost arm 48 overlies the lowermost arm 50 and extends parallel therewith.

Each of the arms 48 and 50 is provided at the outermost ends thereof with finger structure 52 and 54 respectively. The fingers of the uppermost structure 52 comprises elongated, rigid rods 56 swingably coupled to arm 48 by bearings 58 for rotation about the longitudinal axis of arm 48. Each of the fingers of structure 52 terminates in an elongated, resilient section 60 for a purpose to be hereinafter described. It will be noted from FIGS. 1 and 2 that the fingers of structure 52 are of graduated lengths and that the fingers are spaced laterally from one another along arm 48.

The fingers of structure 54 are mounted in a similar manner on the lower most arm 50. In this case, however, each of the lowermost fingers not only includes an elongated rod section 62 and a resilient terminal section 64, but a counterweight section 66 disposed on the opposite side of the axis of rotation of the finger from rod 62. Here again, the fingers of structure 54 are of graduated lengths as illustrated in FIGS. 1 and 2, and the individual fingers are spaced laterally from one another along arm 50.

It will be noted that the fingers of the uppermost structure 52 normally extend downwardly by virtue of their own weight distribution in relationship to their axis of revolution about arm 48. The fingers of structure 52 terminate in opposed, vertically spaced relationship from the terminal ends of the corresponding fingers of the lowermost structure 54 to define therebetween a gap 68. Although the fingers of structure 54 are free to rotate about the axis of arm 50, they normally assume the position illustrated in FIGS. 1 and 2 by virtue of the counterweights 66 on each of the fingers.

Sleeve 42 may be provided with a pair of handles 70 as illustrated in FIG. 1. One of the handles 70 has con-

nected thereto one end of an elongated, flexible element 72 such as a cable, chain or the like which enters section 26 and passes around a pulley 74 mounted in elbow 28 as illustrated in FIG. 4. Element 72 then passes through member 16, around a pulley 76 mounted in elbow 30 as illustrated diagrammatically in FIG. 3, around a pulley 78 mounted in elbow 40, and thence around a pulley 80 carried within the outermost end portion of boom 38. Element 72, extending out of the outermost end of boom 38, is thereupon fastened to a baseball 82 or the like. The opposite side of ball 82 has secured thereto a second flexible element 84 which is trained around a pulley 86 disposed in the outermost end of a boom 88 disposed in vertically spaced relationship beneath the upper boom 38 as illustrated in FIG. 1.

The innermost end of boom 88 communicates with a counterweight assembly 90 illustrated in detail in FIG. 6 of the drawing. Thus, element 84 passes through the tubular boom 88 and is trained around a pulley 92 which is disposed in the lowermost end of a tubular section 94 of assembly 90 which is secured to and extends in parallelism with pipe 34 of upright 12. The element 84 is thereupon passed around a pulley 96 carried at the uppermost end of section 94 adjacent the uppermost end of a second section 98 of assembly 90. The element 84 is thereupon secured to a counterweight 100 which is free to move up and down within the tubular section 98. Manifestly, section 98 is also rigidly secured to pipe 34 alongside section 94.

Leg assembly 20 includes a pair of legs 102 which are foldably mounted to a plate 104 rigidly secured to the lowermost end of pipe 22. Similarly, legs 106 of assembly 18 are foldably secured to a flat plate 108. Plate 108, however, is mounted through connectors 110 to a flat plate 112 which is rigidly secured to elbow 30 as by welding or the like. Set-screws 114 permit plate 112 to be shifted vertically toward or away from plate 108 whereby the entire assembly can be adjusted to accommodate uneven terrain or the like.

In operation, sleeve 42 may be placed at the proper position vertically along pipe 22 to accommodate the strike zone of a batter who wishes to practice his swing with this apparatus. The lengths of elements 72 and 84 are chosen so that the ball 82, which constitutes a target at which the batter may swing, is at the desired height with respect to gap 68 between the opposed ends of the fingers of structure 52 and 54 respectively. It will be readily understood from FIG. 3 that any shifting of sleeve 42 along pipe 22 will result in a corresponding shifting of ball 82 in the same direction. The locations of the respective pulleys are such that the corresponding shifting of ball 82 will also be of the same distance. Counterweight 100 assures that the elements secured to ball 82 remain taut at all times to prevent swinging of ball 82.

The batter viewing target 82 may swing at the latter. If his swing is correct, the bat should swing through gap 68 without contacting any of the fingers of structures 52 or 54. On the other hand, if the batter has not learned the ability to swing the bat through the path of travel which he intends, the bat will deviate from the desired path of travel and will contact one or more of the fingers of structure 52 or 54. Whichever fingers are contacted by the bat will spin on their respective axes of rotation. If the fingers of structure 52 are observed to spin following the swing, the batter is advised that his swing has deviated from the desired path of travel in an upward direction and he can adjust his subsequent swing accordingly. Conversely, if the lowermost fingers are observed to spin following the swing, then the batter will be advised to adjust his swing in an upward direction. Further, because of the graduated lengths of the fingers, the batter receives an indication as to the amount of the deviation in either direction. Accordingly, if only the outermost one of the fingers of either structure is observed to spin following the swing, the batter will know that his deviation has only

been slight from the optimum path of travel. On the other hand, if a plurality of the fingers are spinning, the batter, knowing the increment of difference between the graduated lengths of the respective fingers, is automatically advised as to the distance of the correction which he should make in his subsequent swing.

The resilient outermost sections 60 and 64 of the fingers permits contact by the bat without resulting in damage to the apparatus or to the bat. It is contemplated that the entire finger structure could be made of molded plastic or other yieldable material if desired to accomplish this result.

It will further be readily appreciated by those skilled in the art that a variety of modifications may be made to the structure without departing from this invention. Specifically, if desired, the flexible elements do not necessarily have to be passed along a path of travel within the tubular elements set forth above. On the other hand, the specific construction disclosed herein has been found to be particularly suitable for ready portability of the unit as well as providing an efficient, relatively inexpensive batter's practice apparatus which may be constructed from readily available materials and yet which presents a neat and attractive appearance.

Having thus described the invention, what is claimed as new and desired to be secured by Letters Patent is:

1. Apparatus for testing the swing of a bat comprising:

a frame including an upright;
a pair of vertically spaced arms carried by the upright and extending laterally therefrom; and
yieldable finger structure mounted on each arm respectively, the finger structure on the uppermost of said arms extending downwardly and the finger structure on the lowermost of said arms extending upwardly, said structures and said arms terminating in spaced-apart unconnected ends defining a gap therebetween, said gap being adapted to receive a bat therethrough when the latter is swung, whereby deviation of the swing of the bat from said gap engages a finger structure to indicate the direction of said deviation.

2. The invention of claim 1, said arms being shiftably mounted on said upright for movement up and down the upright to vary the height of said gap.

3. Apparatus for testing the swing of a bat comprising:

a frame including an upright;
a pair of vertically spaced arms carried by the upright and extending laterally therefrom; and
yieldable finger structure mounted on each arm respectively, the finger structure on the uppermost of said arms extending downwardly and the finger structure on the lowermost of said arms extending upwardly, said structures terminating in spaced-apart ends defining a gap therebetween, said gap being adapted to receive a bat therethrough when the latter is swung, whereby deviation of the swing of the bat from said gap engages a finger structure to indicate the direction of said deviation,

said finger structure including a plurality of fingers for each arm respectively,

said fingers being spaced laterally along the arm and the fingers on each arm being of graduated lengths.

4. The invention of claim 3, each of said fingers being swingably mounted on the corresponding arm for rotation about the longitudinal axis of the respective arm.

5. Apparatus for testing the swing of a bat comprising:

a frame including an upright;
a pair of vertically spaced arms carried by the upright and extending laterally therefrom; and
yieldable finger structure mounted on each arm respectively, the finger structure on the uppermost of said arms extending downwardly and the finger structure on the lowermost of said arms extending upwardly, said structures terminating in spaced-apart ends defining a gap therebetween, said gap being

adapted to receive a bat therethrough when the latter is swung, whereby deviation of the swing of the bat from said gap engages a finger structure to indicate the direction of said deviation,
 said arms being shiftably mounted on said upright for movement up and down the upright to vary the height of said gap,
 said apparatus including a ball, and means suspending said ball in horizontally spaced relationship from said gap,
 said suspending means including means interconnecting said ball with the arms for simultaneously altering the height of said ball to correspond with the height of said gap as said arms are moved along the upright.

6. The invention of claim 5, wherein said interconnect-

5

10

15

ing means includes a system of pulleys carried by the frame, and an elongated, flexible element trained around said pulleys and secured to said ball and said arms respectively.
